UNITED STATES PATENT OFFICE.

IRVING W. RUGG, OF BLISS, NEW YORK.

RATCHET-WRENCH.

SPECIFICATION forming part of Letters Patent No. 781,305, dated January 31, 1905.

Application filed July 22, 1904. Serial No. 217,669.

To all whom it may concern:

Be it known that I, IRVING W. RUGG, a citizen of the United States, residing at Bliss, in the county of Wyoming and State of New York, have invented certain new and useful Improvements in Ratchet-Wrenches, of which the following is a specification.

This invention relates to wrenches, and more particularly to that class known as the "ratchet" type; and its object is to produce a device of this character having compactness of construction combined with simplicity and efficiency of parts.

To this end the invention may be said to consist in the details of construction and combination of parts hereinafter set forth in the specification and illustrated in the drawings, wherein—

Figure 1 is a perspective view of the ratchet-wrench. Fig. 2 is a side view showing the forward portion in central vertical longitudinal section. Fig. 3 is a section taken on line 3 3, Fig. 2. Fig. 4 is a vertical section taken on line 4 4, Fig. 3. Fig. 5 is a central transverse vertical section through the head of the wrench. Fig. 6 is a vertical section taken on line 6 6, Fig. 3. Fig. 7 is a fragmentary longitudinal section taken on line 7 7, Fig. 2. Fig. 8 is a fragmentary bottom plan view of the same, showing the locking-plate. Fig. 9 is a modified construction of the pawl.

The letter A indicates the handle, having a bifurcated forward end forming a transverse chamber a, and B is the head, fixed to the bifurcated portion of the handle and comprising an upright side wall b, having an annular inner surface, and a bottom wall b', extending inward from the side wall and formed integral with the entire lower edge thereof. Side wall b is provided with an opening b² adjacent the transverse chamber a, while bottom wall b' has a central aperture b³.

C is the wrench member, of cylindrical shape, fitting within head B, with its lower face resting upon the bottom wall thereof. Member C has a central vertical aperture c and is further provided on its lower face with a hub c', forming an annular shoulder c² around the aperture. Hub c' is of a depth equal to the thickness of the bottom wall, so

that when the lower face of the wrench member rests upon the upper face of bottom wall b' the bottom face of the hub is flush with the lower face of this wall. The annular shoulder c² is of such diameter as to fit closely 55 though rotatably within aperture b³. A removable locking-plate D is secured by screws d to the bottom face of hub c' and is of sufficient diameter to overlap bottom wall b' of the head. It is furnished with an aperture d', 60 that registers with aperture c in the wrench member. By the construction just described the wrench member is afforded a broad and firm bearing against the bottom wall of the head, while the wrench and head are held in 65 close but rotatable connection, whereby the looseness of construction often found in tools of this type is avoided. Upon the lower portion of its lateral surface the wrench member is provided with a series of ratchet-teeth 70 E, which stand wholly within the side wall of the head, thereby preventing said teeth from catching the hands or clothing of the operator. By means of teeth E the wrench member is adapted to be operatively connected with the handle through a pawl member F, which is pivoted in transverse chamber a at the forward end of the handle. This pawl member comprises two forwardly-projecting arms f and a body portion f', having rearwardly-converging side walls f². A latch G, comprising a head g, having forwardly-converging walls g' and a shank g², is located in rear of the pawl member and is adapted to hold the latter with one or other 75 of its arms f in engagement with teeth E. For this purpose shank g² is seated slidably within a longitudinal chamber g³ in rear of and communicating with transverse chamber a, and a coil-spring g⁴ is placed around the 80 shank outside of said chamber, operating to protrude the head, whereby, as shown in Fig. 7, one of the lateral faces of the pawl member is held in engagement with the diagonally opposite face of the latch-head. A longitudinal slot g⁵ is formed in the top wall of the transverse chamber a above and in front of longitudinal chamber g³, and a pin g⁶ projects upwardly from the head of the latch through the slot, affording means for permitting shift- 85

ing of the pawl member and serving as an additional guide for the latch to prevent possible breakage or binding during the reciprocation of the latch. As the shank of the latch 5 is subject to considerable strain at such times, it is obviously of advantage to provide guides both at front and rear.

In Fig. 9 is illustrated a modified form of pawl member, in which its rear portion is 10 provided with a rearwardly-projecting pin g' , which is engaged by the front end of a spring g'' , that serves to hold the pawl member on one side or other of its center.

In the upper portion of the wrench member 15 is formed a transverse guideway H of inverted-T shape in cross-section, which intersects the upper end of upright aperture c . Adjacent to this guideway and communicating with it through its widened lower portion 20 only, as at i' , are two open-topped chambers I , which are connected with each other by a reduced intermediate groove i and with the lateral face of the wrench member by reduced grooves i' .

The letter K indicates two jaws having 25 their lower portions formed in T shape to slide within the guideway. The portions of jaws K adjacent the openings i' in chambers I are formed with worm-teeth k , that engage 30 with a worm-gear L , located in the chambers and grooves. The gear L comprises two portions l , having opposite threads, an intermediate smooth reduced portion l' , lying in intermediate groove i , and smooth reduced portions l'' , that lie within end grooves i' and project beyond the lateral surface of the wrench member. End portions l'' are journaled in 35 removable bearings b' , that are secured to the lateral surface of the wrench member at the 40 ends of end grooves i' . Bearings b' are secured to the wrench member by screws t' , thereby making the bearings and worm-gear readily removable. By the foregoing 45 construction the worm-gear is reliably held against longitudinal movement, thereby preventing disturbance of the adjustment of the jaws, while owing to the accessible mounting of the gear this part, which is usually the portion of the tool to become worn, may be easily replaced. One end of the worm-gear is provided with the usual milled head l'' .

What is claimed as new is—

1. In a device of the character described, the combination with the handle, a head fixed 55 at the forward end thereof, a wrench member mounted in said head and having a transverse guideway formed therein and a chamber parallel to and communicating with said guideway, and means for rotating the wrench member; of oppositely-disposed jaws operating in 60 said guideway and having worm-teeth formed on their sides adjacent said chamber, and a worm-gear fitting within said chamber and having oppositely-disposed threads engaging 65 with the teeth on the jaws.

2. In a device of the character described, the combination with the handle, a head fixed at the forward end thereof, a wrench member mounted in said head and having a transverse guideway formed therein and a chamber having 70 open top and ends parallel to, and communicating with said guideway, and means for rotating the wrench member; of oppositely-disposed jaws operating in said guideway and having worm-teeth formed on their sides adjacent said chamber, and a worm-gear fitting 75 removably within said chamber and having oppositely-disposed threads engaging with the teeth on the jaws.

3. In a device of the character described, the combination with the handle, a head fixed at the forward end thereof, a wrench member mounted in said head and having a transverse guideway formed therein and a chamber having 80 open top and ends parallel to, and communicating with said guideway, and means for rotating the wrench member; of oppositely-disposed jaws operating in said guideway and having worm-teeth formed on their sides adjacent said chamber, a worm-gear fitting 85 removably within said chamber and having oppositely-disposed threads engaging with the teeth on the jaws, and removable bearings for the gear mounted on the sides of the wrench member at the open ends of the chamber. 90

4. In a device of the character described, the combination with a handle, a head fixed at the forward end thereof, a wrench member mounted in said head and having a transverse guideway formed therein, the wrench member being further provided with two open-topped chambers communicating with said guideway at their bottoms only, an open-topped intermediate groove narrower than 100 said chambers and connecting the inner ends thereof, and two open-topped end grooves also narrower than the chambers and leading from the outer ends thereof through the sides of the wrench member, and means for rotating the wrench member; of oppositely-disposed jaws operating in said guideway and having worm-teeth formed on their sides adjacent said chambers, a removable worm-gear having oppositely-threaded portions lying in 105 the chambers and engaging with said teeth, a smooth reduced portion lying in the intermediate groove, and smooth reduced ends lying in the end grooves and projecting from the sides of the wrench member, and removable bearings for the last-named reduced portions 110 mounted on the sides of the wrench member at the ends of said grooves.

In testimony whereof I have affixed my signature in the presence of two subscribing witnesses.

IRVING W. RUGG.
